ELECTRIC CHAIN SAW

Charles A. Latimer, Toledo, Ohio, assignor to The American Floor Surfacing Machine Company, Toledo, Ohio, a corporation of Ohio

Application September 10, 1953, Serial No. 26,758

Term of patent 14 years

(Cl. D93—3)

To all whom it may concern:

Be it known that I, Charles A. Latimer, a citizen of the United States, and resident of Toledo, in the county of Lucas and State of Ohio, have invented a new, original, and ornamental Design for an Electric Chain Saw, of which the following is a specification, reference being had to the accompanying drawings, forming a part thereof.

In the drawings,

Fig. 1 is a perspective view of an electric chain saw, showing my new design;

Fig. 2 is a front end view thereof;

Fig. 3 is a perspective view of the opposite side of the electric chain saw from that shown in Fig. 1;

Fig. 4 is a rear end view thereof, and Figs. 5 and 6 are respective top and bottom views thereof.

I claim:

The ornamental design for an electric chain saw, substantially as shown.

CHARLES A. LATIMER.
